UNITED STATES PATENT OFFICE.

WILLIAM H. LAMB, OF ATTLEBORO, MASSACHUSETTS, ASSIGNOR TO C. H. ALLEN & CO., OF ATTLEBORO, MASSACHUSETTS.

HOT-BLAST DRYING-MACHINE.

No. 920,585.

Specification of Letters Patent.

Patented May 4, 1909.

Application filed December 12, 1908. Serial No. 467,287.

To all whom it may concern:

Be it known that I, WILLIAM H. LAMB, a citizen of the United States, residing at Attleboro, in the county of Bristol and State of Massachusetts, have invented a new and useful Improvement in Hot-Blast Drying-Machines, of which the following is a specification.

This invention has reference to an improvement in drying machines and more particularly to an improvement in hot blast drying machines for drying articles of jewelry or similar articles.

The object of my invention is to improve the construction of a hot blast drying machine for jewelry, whereby the drying of articles of jewelry is greatly facilitated and the time required for drying the same materially reduced.

20 A further object of my invention is to construct a hot blast drying machine so that enameled articles of jewelry may be dried or baked simultaneously with the drying of wet articles of jewelry, thereby reducing the 25 cost of drying and baking both kinds of jewelry.

A still further object of my invention is to reduce the cost of manufacturing hot blast drying machines for jewelers' use by simplifying the construction of the same.

My invention consists in the peculiar and novel construction of a hot blast drying machine having a hollow body, an air heating chamber in the body, a coil of steam pipes in the air heating chamber, a baking oven in the body, a drying receptacle in the top of the body, a blower connected with the heating chamber, a pipe leading from the blower to the drying receptacle, and details 40 of construction, as will be more fully set forth hereinafter and claimed.

Figure 1 is a vertical sectional view taken centrally through my improved hot blast drying machine on a line with the blower, and Fig. 2 is a horizontal sectional view taken on line 2-2 of Fig. 1 through the drying machine.

In the drawings, *a* indicates a hollow cylindrical body constructed to form a drying receptacle *b*, a heating chamber *c* and a baking oven *d*, *e* a coil of steam pipes in the heating chamber *c*, *f* a blower, *g* a pipe leading from the heating chamber *c* to the blower *f* and *h* a pipe leading from the blower *f* to the drying receptacle *b*.

The body *a* is constructed preferably of sheet metal and shaped to have the sides 3, the closed bottom 4 and top 5, and is supported on the legs 6 6, the rear one of which is formed to have the bracket 7 for supporting the blower *f* as shown in Fig. 1.

The drying receptacle *b* forms a part of the top 5 and has the open top 8, the closed bottom 9 and sides 10 in the front of which are the perforations 11 and extends downward centrally from the top 5 into the heating chamber *c*.

The heating chamber *c* is formed by the sides 3 and top 5 of the body *a*, the bottom 9 and sides 10 of the drying receptacle *b*, and a lateral partition 12 forming the bottom of the chamber.

The baking oven *d* is formed by the sides 3 and bottom 4 of the body *a* and the lateral partition 12, forming the top of the oven, which has a rectangular opening 13 in the side closed by a door 14.

The steam coil *e* is placed at an angle in the heating chamber *c* adjacent the bottom 12 and under the drying receptacle *b*, as shown in Fig. 1, and is connected to a source of steam supply under pressure (not shown) by a pipe 15.

The blower *f* has the pulley 16 for operating the same and may be any form of a blower adapted to suck the hot air from the chamber *c* through the pipe *g*, which connects the chamber with the blower, and forces the hot air through the pipe *h* which extends upward from the blower and is shaped to bring the open outlet end 17 of the pipe downward into the drying receptacle, *b*, as shown in Fig. 1.

In the operation of my improved hot blast drying machine the wet articles of jewelry are placed in the drying receptacle *b*, the enameled articles of jewelry placed in the oven *d*, steam under pressure turned into the steam coil *e* and the blower *f* operated by the pulley 16 in the usual way. Air is now sucked by the blower *f* from the drying receptacle *b* through the perforations 11 in the same, then through the heating chamber *c* and steam coil *e*, where the air is dried and heated, and out through the pipe *g* to the blower *f* from which the hot air is now forced through the pipe *h* and out through the open end 17 of the pipe onto and through the wet jewelry. A constant blast or circulation of hot air is now kept up through the jewelry, 110

thoroughly drying the same in the shortest possible time. The enameled articles are left in the oven *d* the required time to properly dry or bake the same.

5. It is evident that any means may be used for heating the air in the heating chamber *c* without materially affecting the spirit of my invention.

Having thus described my invention, I 10 claim as new and desire to secure by Letters Patent:-

1. In a drying machine, a drying receptacle, a heating chamber under the drying receptacle, means for connecting the drying 15 receptacle with the heating chamber, a baking oven, means for heating the heating chamber and the oven, and means for constantly circulating the hot air from the heating chamber out and back through the drying 20 receptacle into the heating chamber.

2. In a drying machine, a heating chamber, an open top drying receptacle extending downward into the heating chamber and having openings connecting the drying receptacle 25 with the heating chamber, a baking oven under the heating chamber, means for heating the chamber and oven, and means for constantly circulating the hot air from the heating chamber out and back through the 30 drying receptacle into the heating chamber.

3. A hot blast drying machine having a hollow body, a heating chamber in the body, an open top drying receptacle extending from the top downward into the heating 35 chamber and having openings connecting the drying receptacle with the heating chamber.

ber, a blower, a pipe connecting the heating chamber with the blower, a pipe connected with the blower and having its open end extending downward into the drying receptacle 40 and means for heating the heating chamber.

4. A hot blast drying machine having a hollow body, a heating chamber in the body, an open top drying receptacle extending from the top of the body downward into the 45 heating chamber and having openings connecting the drying receptacle with the heating chamber, an oven in the body under the heating chamber, a blower, a pipe connecting the heating chamber with the blower, a pipe 50 connected with the blower and having its open end in a position to extend downward into the drying receptacle, and means for heating the air in the heating chamber and the oven.

5. In a hot blast drying machine, the combination of the following instrumentalities: a hollow body *a* formed to have the drying receptacle *b*, the heating chamber *c* and the baking oven *d*, a steam coil *e* in the heating 60 chamber *c*, a blower *f*, a pipe *g* connecting the heating chamber *c* with the blower *f*, and a pipe *h* connected with the blower *f* and having its open end extending downward into the drying receptacle *b*.

In testimony whereof I have hereunto signed my name to this specification in the presence of two subscribing witnesses.

WILLIAM H. LAMB.
